Inventor—

Louis A. Gignac

United States Patent Office.

LOUIS A. GIGNAC, OF TROY NEW, YORK, ASSIGNOR TO HIMSELF
AND P. POLLOCK, OF SAME PLACE.

Letters Patent No. 94,197, dated August 31, 1869.

IMPROVEMENT IN CURRIERS' KNIVES.

The Schedule referred to in these Letters Patent and making part of the same.

To all whom it may concern:

Be it known that I, LOUIS A. GIGNAC, of Troy, in the county of Rensselaer, and State of New York, have invented a certain useful new Improved Currying-Knife; and I do hereby declare that the following is a full and exact description of the same, reference being had to the accompanying drawings and letters of reference marked thereon, making a part of this specification, in which—

Figure 1 is a plan or side view of said knife, and

Figure 2 is a longitudinal vertical section of the same.

The same letters refer to like parts in each of said figures.

In order to get strength in the shanks of carrying-knife stocks to resist twisting strains thereat, when using the knife, the shanks thereof have been made in two pieces, by continuing the shanks of both of the parts or jaws of the stock through the handles of the knife and holding the shanks together and handles thereon by a nut screwed on a thread cut around both parts of the shank.

In using currying knives, the blades thereof have frequently to be removed from the stock to be cleaned and oiled to prevent their rusting in the stock, and, in the knife-stock above mentioned, it is found inconvenient and troublesome to be obliged so often to remove the handles from the knife-stock, in order to simply clean and oil the gripping-faces of the stock and the knife-blades; and

The object of my invention is to construct a currying-knife stock, having strong handle-shanks, and in such a manner that the knife-blades may be easily removed therefrom without disturbing the handles; and

My invention consists in a new and improved manner of holding the stock-jaws and blades of a currying-knife together, and in attaching the cross-handle to the knife-stock, so that the holding-jaw is easily removed from the stock-jaw to clean the jaws and blades thereof, without disturbing the handles of the knife.

To enable others to make my said improved currying-knife, I will now fully describe its construction, as follows:

The permanent jaw A of the knife-stock is made, at one of its shank-ends, in a hook-like shape, substantially as shown at E in fig. 2. Said shank is then continued through the handle D, which is permanently secured thereon.

The shank at the other end of said jaw A is made in a cross-head form, as at H I I, substantially as

shown in figs. 1 and 2; and in the cross-head part there is made a recess or socket, a.

The cross-handle C is permanently secured to said cross-head shank by letting the cross-part of said shank flush into the handle in manner so that its edge sides are shouldered in the handle, and then riveting the handle to said cross-shank by the rivets b b, in manner as shown in fig. 1.

The removable jaw B is made with a tongue, F, at one end, which fits into the hook-like socket E aforesaid, and it is held therein by the pin or screw d passing through the tongue and hook.

The other end of the removable jaw, at G, is made in a rounded or slightly tapering shape, so that its end shall fit into the socket a in the cross-shank I I, in manner substantially as shown in figs. 1 and 2.

The removable jaw B is attached to the permanent jaw A by first slipping its end G into its socket a, then passing its tongue F into the hook-like groove E, and securing it therein by the pin or screw d. The tightening-screws c c are then put in, and the knife-blades J J slipped into and adjusted in their respective places between the jaws A and B. Then the holding-screws e are screwed tight, thus causing the jaws to gripe and hold firmly the said blades.

When necessary to remove the jaw B and knife-blades, to clean and oil the gripping-faces of the jaws and the blades, it is easily done, without disturbing the handles D C, by first taking out the screws e, then the pin d, when the jaw B may be moved out free of the hook E and socket a, thus, in a convenient manner, enabling the jaw B and knife-blades to be removed, cleaned, and oiled, to prevent their corrosion by water or moisture.

Having thus described my improvement,

What I claim, and desire to secure by Letters Patent, is—

An improved currying-knife, having at one end of its removable jaw B a tongue, F, to fit into a hook-like socket, E, at one end of the permanent jaw A, while the other end G fits into a socket, a, in the cross-shank I I of said jaw A, and having the cross-handle C secured thereto, by means of said cross-shank and rivets b b, combined with blades J J and tightening-screws c, in manner substantially as described, for the purposes set forth.

LOUIS A. GIGNAC.
